PORTABLE RACK FOR VACUUM CLEANER AND ATTACHMENTS

Norman L. Bassin, Los Angeles, Calif.

Application August 2, 1948, Serial No. 147,888

Term of patent 3½ years

(Cl. D80—9)

To all whom it may concern:

Be it known that I, Norman L. Bassin, a citizen of the United States of America, a resident of the city of Los Angeles, in the county of Los Angeles and State of California, have invented a new, original, and ornamental Design for Portable Rack for Vacuum Cleaners, and attachments, of which the following is a specification, reference being had to the accompanying drawing which forms a part thereof.

In the drawings:

Fig. 1 is an elevational view of a portable rack for vacuum cleaner and attachments, showing my new design;

Fig. 2 is a side elevational view showing the opposite side.

Figure 3 is a top plan view thereof,

Figure 4 is an end elevational view thereof.

The broken lines shown in Figs. 1 and 2 are for illustrative purposes only.

The underside portion of the portable rack for vacuum cleaner and attachments is plain.

I claim:

The ornamental design for a portable rack for vacuum cleaner and attachments, as shown and described.

NORMAN L. BASSIN.
